UNITED STATES PATENT OFFICE.

VAN VINCENT CURTIS, OF McALLEN, TEXAS.

AUTOMOBILE JACK.

Application filed February 8, 1923. Serial No. 617,763.

To all whom it may concern:

Be it known that I, VAN V. CURTIS, a citizen of the United States, residing at McAllen, in the county of Hidalgo and

5 State of Texas, have invented a new and useful Automobile Jack, of which the following is a specification.

This invention relates to lifting jacks, and more particularly to lifting jacks especially designed for use in connection with 10 motor vehicles or the like.

The primary object of the invention is to provide a quick-acting jack, whereby the article being lifted may be moved to the 15 desired position by a single operation of the lifting lever.

Another object of the invention is to provide a jack which will be automatically locked in its positions of adjustment.

20 A still further object of the invention is to provide a jack which may be folded into a small and compact article to facilitate the storing thereof and permit the same to be carried in the usual tool kit.

25 With the foregoing and other objects in view which will appear as the description proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

35 Referring to the drawing:—

Figure 1 is a vertical sectional view through a jack constructed in accordance with the present invention, the operating 40 lever being shown in dotted lines in its folded position.

Figure 2 is a sectional view taken on line 2—2 of Figure 1.

45 Referring to the drawing in detail, the reference character 5 designates the base of the jack which is formed with a longitudinal central bore provided with threads indicated at 6.

50 The jack also embodies a threaded shaft indicated at 7 adapted to move in the base, the threads of the shaft cooperating with the threads of the base to permit of an

adjustment of the shaft with respect to the base to raise and lower the same.

Formed at the upper end of the shaft 7 is a head 8 which is formed with a cut out portion 9 to accommodate the ratchet bar 10 which moves therethrough, the ratchet bar being curved, as clearly shown by Figure 1 of the drawings and bolted 55 to the lever 11 as at 12. A pivoted pawl is also supported between the walls of the cut out portion 9 and is designed to contact with the teeth of the ratchet bar 10 to hold the lever 11 in its positions of adjustment, the pawl being such as to automatically fall to its active position. 60 65

Formed integral with the lever 11 is a depending bearing member 14 which is also disposed between the walls of the cut out portion 9 and pivotally supported on the pin 15. One end of the lever 11 extends beyond the vertical plane of the base 5 and is formed into a curved supporting surface 16, the curvature thereof conforming to the 70 curvature of an axle to embrace a portion of an axle and prevent movement of the axle with respect to the jack proper. 75

An extension handle is indicated at 17 and is hingedly connected to the lever 11 so 80 that great leverage of the lever 10 may be had, due consideration being given to the compacting of the jack.

In the use of the device, the threaded shaft 7 is rotated, to bring the article engaging extremity 16 of the lever 11 into proximity with the article to be lifted, whereupon the lever is operated in a manner as described, with the result that the articles engaged by the portion 16 of the lever is elevated, the pawl automatically moving to lock the lever in its supporting position. 85 90

Having thus described the invention, what is claimed as new is:—

95 A lifting jack including a base, a threaded shaft movable through the base and having a head, said head having a cut out portion, a lever pivotally supported by the head, a curved ratchet bar secured to the lever and movable between the walls of the cut out portion, the ratchet bar having teeth formed on the upper surface thereof, a pawl pivotally supported within the walls 100

of the cut out portion and disposed above the ratchet bar, said pawl adapted to automatically fall by gravity into engagement with the ratchet bar to lock the lever in its positions of adjustment, and said lever having a curved article engaging extremity.

In testimony that I claim the foregoing

as my own, I have hereto affixed my signature in the presence of two witnesses.

VAN. VINCENT CURTIS.
